CLAIM

The ornamental design for a LED bulb as shown and described.

DESCRIPTION

1. LED bulb
2. LED bulb
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom

The broken lines represent portions of the LED bulb in which the design is embodied that form no part of the claimed design.
